Primary Examiner—M. N. Pandozzi**Attorney, Agent, or Firm—James G. O'Neill****[57] CLAIM**

The ornamental design of a lap tray, as shown and described

DESCRIPTION

FIG. 1 is a top plan view of a lap tray showing my new design;

FIG. 2 is a front elevational view of FIG. 1; the rear view being identical to the front view as shown;

FIG. 3 is a bottom plan view of FIG. 1;

FIG. 4 is a side elevational view of FIG. 1; the other side view being identical to that shown;

FIG. 5 is a top plan view of a lap tray showing a second embodiment of my new design;

FIG. 6 is a front elevational view of FIG. 5; the rear view being identical to the front view as shown;

FIG. 7 is a bottom plan view of FIG. 5; and,

FIG. 8 is a side elevational view of FIG. 5; the other side view being identical to that shown.
